UNITED STATES PATENT OFFICE

HOWARD D. RANDALL, OF CINCINNATI, OHIO, ASSIGNEE TO THE RANDALL COMPANY,
OF CINCINNATI, OHIO, A CORPORATION OF OHIO

RUBBER SET HAIR WINDOW CHANNEL

Application filed December 12, 1930. Serial No. 501,870.

This invention relates to that class of devices known as window channels or guides such as are commonly employed in automobile bodies to hold slidably the usual window glass.

A window guide which will satisfactorily meet all the demands of the maker and user necessarily must hold the glass rigidly against vibration and yet prevent binding between the glass and the guide. It must not be affected adversely by time, dirt, climatic or weather conditions. It must admit of ready assembly; be relatively inexpensive to manufacture, and when once installed give maximum service.

In an endeavor to meet these exacting demands various materials including rubber, felt, fabric and metal heretofore have been proposed but none of them has been entirely satisfactory.

This invention has for its primary object to provide an improved window channel, which will be devoid of all the inherent defects of prior constructions, and will meet all the demands of the trade. More specifically stated, it provides a window channel which will not dry out and thereby present to the glass a hard unyielding surface as does rubber; which will not absorb and retain water and thereby swell and cause binding on the glass, as do felt and fabric; which does not permit rattle or cause binding as does metal, dependent whether it is loose or snug on the glass; but which will, under all conditions, provide the proper cushioning effect for the glass and the requisite amount of friction thereon.

This object of constructing an improved window glass channel has been attained by providing a relatively heavy fibrous base and by securing to said base, due to their being vulcanized in a waterproof sheet of rubber, cemented or otherwise attached to the base, a myriad of relatively stiff hairs, preferably goat's hair, which project perpendicular to the face of the rubber sheet, thereafter folding a strip of said composite sheet into a substantially U-shape channel and securing it within the usual rabbet commonly provided for the purpose. With the strip so

folded there is provided a central longitudinal groove of which the sides and bottom are formed by hairs standing on end and adapted frictionally to engage the glass inserted therein, and there is preferably sufficient frictional engagement between the ends of the hairs and glass member to support said member in its various positions, except under strains incident to the moving vehicle, which insures that there will be sufficient frictional engagement to prevent undesirable rattling.

If desired, strips of suitable material, such for example as metal or celluloid, may be secured to the fibrous base at the side opposite to that to which the hairs project thereby to stiffen the glass channel.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is a perspective view of the strip of material from which the improved window channel may be made. Fig. 2 is a sectional view showing the improved window channel located within the usual rabbet formed in the window frame and held in place by the usual garnish moulding. Fig. 3 is a view similar to Fig. 1 but showing the strip grooved for a purpose hereinafter to be explained. Fig. 4 is a disassembled perspective view of the strip shown in Fig. 3 folded into U-shape, together with the stiffening strips adapted to be secured thereto. Fig. 5 is a view similar to Fig. 2 but showing the channel formed of the elements illustrated in Fig. 4. Fig. 6, 90 is a perspective view similar to Fig. 3 but showing in addition stiffening plates adhesively secured to the back of the strip. Fig. 7 is a perspective view showing the strip illustrated in Fig. 6 folded into U-shape form. 100

Figs. 8 and 9 are detail sectional views illustrating the bending action of the hairs as the glass is moved in opposite directions.

Referring more specifically to the drawings and particularly to Figs. 1, 2, 8 and 9, the improved window channel is disclosed as comprising a base 1 of fabric or other suitable flexible material to which is secured, by any suitable means such, for example as by 10 cement 2, a sheet 3 of rubber or other waterproof material. Embedded into or otherwise secured to the sheet 3 are a myriad of relatively stiff hairs 4 which project outwardly perpendicular to the face of the rubber sheet. When the strip is folded into U-shape 15 form, as shown in Fig. 2, the hairs form a cushion for the glass 5 slideable in the central longitudinal groove therebetween. Goat's hair has been found admirably well suited 20 for this purpose as it is sufficiently stiff to stand up satisfactorily under the adverse conditions to which such devices are subjected and to afford the necessary friction, yet sufficiently flexible to bend as the direction of 25 movement of the glass is changed thereby preventing undue binding on the glass. The use of other relatively stiff hair is, however, contemplated.

As shown in Fig. 2 this improved channel 30 may be inserted directly in the rabbet 6 formed in the frame 7 and held therein by a garnish molding 8, suitably secured to the frame. To hold the channel in place in the rabbet the frame is formed with a lip 7^a and 35 the garnish moulding with a lip 8^a which engage the edges of the channel strip.

If desired the sheet of waterproof material may be made heavier and the fabric base 1 dispensed with. Also the hairs may be ar- 40 ranged to engage the sides only of the glass, other means being provided to prevent edge-wise movement of the glass.

Among the advantages attained by the present window channel is that the entire 45 groove for the glass is provided with a waterproof lining which prevents deterioration commonly experienced with other forms of guides due to their repeatedly being subjected to water. Furthermore, due to the fact 50 that the hairs are relatively stiff and thereby stand somewhat spaced apart they permit free passage of water therebetween, therefore the channel does not retain water as does felt or fabric but instead is quick drying. 55 Still further neither the rubber lining nor the hairs swell when subjected to water nor do the hairs readily lose their resiliency. Therefore the friction between the glass and the guide channel is substantially constant 60 under all conditions of use.

Still another advantage is that it may more readily be inserted in the usual frame and assembled with the glass therein than any prior constructions. Referring to Fig. 2 it 65 will be perceived that with the garnish

moulding removed from both sides of the window strips similar to those shown in either Figs. 1 or 3 may be folded into L-shape form and inserted into the rabbets 6, provided by the opposite sides of the frame 7, 70 with one edge thereof in engagement with the lips 7^a and the main body of the strips extending along the faces 7^b of the frame as shown in dotted lines, Fig. 2. Then the glass may be inserted by a horizontal movement 75 in a direction perpendicular to the face of the glass, next the other side of the strip may be folded against the glass, thus completing the U-shape and the garnish moulding may be attached to the frame to hold the 80 parts in their assembled position.

As shown in Fig. 9 the hairs 4 are of such length that the channel therebetween is of slightly less width than the glass adapted to slide therein. This causes the hairs always 85 to exert a slight pressure on the glass thereby producing the requisite friction thereon. During movement of the glass the hairs will bend in the direction of such movement, as illustrated in Figs. 8 and 9. 90

If desired the mat of hair on the strip may be grooved longitudinally as shown at 9. This may be effected in any suitable way such, for example, as by removing the hairs from a portion of the strip. These grooves 95 form a clearance and permit ready bending of the strip into U-shape form, as shown in Fig. 4, without compacting the hairs at the corners.

For certain purposes it may be desired to 100 reinforce the channel. This may be effected, as shown in Figs. 4 and 5 by securing to the side and back walls of the channel metal strips 10 and 11. The side strips 10 preferably are formed with hooked extremities 10^a 105 adapted to encase the forward edge 1^a of the flexible base thereby protecting said edge against wear and weather. The strips 10 and 11 may be secured to walls of the channel by 110 having a series of tongues 12 punched therefrom and inserted through the base fabric 1 forming stitches about which the parts are folded as shown in Fig. 5.

Figs. 6 and 7 illustrate another form of 115 stiffening means for the channel. This consists of strips 13 of celluloid or other suitable material adhesively secured to the back of the base strip 1, the strips 13 being separated along the lines at which the base strip is adapted to be folded. In this form also the 120 reinforcing strips are adapted to cover the marginal edges of the base strip as shown at 13^a.

Without further analysis, the foregoing 125 will so fully reveal the gist of this invention that others can, by applying current knowledge, readily adapt it for various utilizations by retaining one or more of the features that, from the standpoint of the prior art, fairly constitute essential characteristics of either 130

the generic or specific aspects of this invention and, therefore such adaptations should be, and are intended to be, comprehended within the meaning and range of equivalency of the following claims:

Having thus revealed this invention, I claim as new and desire to secure the following combinations and elements, or equivalents thereof, by Letters Patent of United States:—

1. A window channel formed from a strip of fabric having a base, a waterproof flexible lining and stiff filaments of hair having their free ends embedded in and projecting from said lining, the fabric being bent to form a central longitudinal depression having the free ends of the filaments of hair forming the sides and bottom of said depression, said central longitudinal depression being capable of receiving a slidable rigid member which will cause said filaments of hair to be bent during its sliding movement.

2. A window channel comprising a fibrous base of substantially U-shape form; a waterproof coating on the inner surface of said base relatively stiff filaments of hair each embedded in said waterproof coating; and having their ends projecting therefrom and constituting yieldable walls of a central longitudinal groove.

3. A window channel comprising a substantially U-shaped base; a waterproof lining in said base; and a plurality of relatively stiff filaments of hair each embedded in said lining and having their free ends projecting therefrom and forming brush-like walls of a central longitudinal glass-receiving groove.

4. A window channel comprising a strip of fibrous material; a coating of rubber on one side of said strip; filaments of hair vulcanized into said rubber and having ends projecting therefrom; and means to hold said strip in substantially U-shape form with the projecting ends of said hairs forming cushioning walls of a central longitudinal groove adapted to receive a window glass.

5. A window channel formed from a strip of fabric having a flexible lining and stiff filaments of hair secured thereto with their free ends projecting beyond said lining, the fabric being bent to form a central longitudinal groove having the free ends of the filaments of hair forming the sides of said groove and capable of supporting a slidable rigid member inserted within said groove.

6. A window channel comprising a U-shaped strip of waterproof material having secured to its inner walls filaments of relatively stiff hair which project perpendicular to the walls of said strip and form a frictional brush-like contact for a glass slidingly mounted therein.

7. A window channel comprising a strip of rubber U-shaped in cross section having filaments of relatively stiff hair vulcanized into

its inner surface, said hairs projecting in opposite directions from the inner side walls of said strip and forming between their adjacent ends a glass receiving groove of a width slightly less than the glass to be inserted therein, said hairs engaging said glass and being flexed in opposite directions when the glass is raised and lowered.

8. A window channel comprising a base of fibrous material substantially U-shaped in cross section, a coating of rubber on the inner side thereof; filaments of hair secured to said rubber and having portions projecting perpendicular to the faces thereof; metallic side plates secured upon the outer faces of the projecting side walls of said U-shaped base and having hooked portions encasing the marginal portions thereof; and a metallic back plate secured upon the outer face of that portion of the base connecting the side walls.

9. A window channel comprising a base of fibrous material substantially U-shaped in cross section; a coating of rubber on the inner side thereof; filaments of hair secured to said rubber and having portions projecting perpendicular to the faces thereof; substantially rigid side plates upon the outer faces of the projecting side walls of said U-shaped base and having hooked extremities encasing the marginal portions of said base; and tongues projecting inwardly from said side plates and extending into said base material to hold said plates on said side walls.

10. A window channel comprising a base of flexible material substantially U-shaped in cross section; a coating of rubber on the inner face thereof; filaments of hair secured to said rubber and having portions projecting perpendicular to the face thereof; and strips of celluloid adhesively secured to outer rear and side walls of said U-shaped base, the strips on the side walls having portions overlying the edges of said base material.

In witness whereof, I have hereunto subscribed my name.

HOWARD D. RANDALL.
